UNITED STATES PATENT OFFICE

113,207

DESIGN FOR A TEXTILE FABRIC

Anna Kojetinsky, Jackson Heights, N. Y., assignor or to Pacific Mills, Lawrence, Mass., a corporation
of Massachusetts

Application February 12, 1938, Serial No. 75,111

Term of patent 3½ years

To all whom it may concern:

Be it known that I, Anna Kojetinsky, a citizen of the United States residing at 72-15 37th Avenue, Jackson Heights, in the county of Queens and State of New York, have invented a new,
original, and ornamental Design for Textile Fabrics, of which the following is a specification,
reference being had to the accompanying drawing, forming a part thereof.

The figure is a plan view of a textile fabric
showing my new and original design.

The repeat angle is indicated by the letter "A"
which corresponds with angle "B" showing how
the unit is repeated.

I claim:

The ornamental design for a textile fabric, as shown and described.

ANNA KOJETINSKY.
